UNITED STATES PATENT OFFICE

151,578

DESIGN FOR AN OCCASIONAL TABLE

Lewis Appell and Nathaniel Appell,
New York, N. Y.

Application March 30, 1946, Serial No. 128,105

Term of patent 3½ years

(Cl. D33—14)

To all whom it may concern:

Be it known that we, Lewis Appell and Nathaniel Appell, citizens of the United States, residing at New York, in the county of the Bronx and State of New York, and whose postoffice address is 395 E. Mosholu Parkway N., Bronx, N. Y., have invented a new, original, and ornamental Design for an Occasional Table, of which the following is a specification, reference being made to the accompanying drawing, forming a part thereof.

Fig. 1 is a front elevational view of an occasional table, showing our new design;

Fig. 2 is a top view of Fig. 1;

Fig. 3 is a sectional view taken through 3—3 of Fig. 1; and

Fig. 4 is a side view of one of the legs shown in Fig. 1.

We claim:

The ornamental design for an occasional table, substantially as shown.

LEWIS APPELL.
NATHANIEL APPELL.
